DESIGN FOR A CLOTHESPIN

Finn Trogstad and Martin O. Berg, Bethesda, Md.

Application September 27, 1945, Serial No. 122,366

Term of patent 14 years

(Cl. D17—6)

To all whom it may concern:

Be it known that we, Finn Trogstad, a citizen of the United States and resident of Bethesda, in the county of Montgomery, State of Maryland, and Martin O. Berg, a citizen of Norway and resident of Bethesda, in the county of Montgomery, State of Maryland, have invented a new, original, and ornamental Design for Clothespins, of which the following is a specification, reference being had to the accompanying drawing, forming a part thereof.

We claim:

The ornamental design for a clothespin, as shown.

FINN TROGSTAD,
MARTIN O. BERG.
